(57) **CLAIM**

The ornamental design for a body-worn mobile device, as
shown and described.

DESCRIPTION

FIG. 1 is a front perspective view of a body-worn mobile device showing our new design coupled to a peripheral device in broken lines;

FIG. 2 is an enlarged perspective view of the invention of FIG. 1;

FIG. 3 is a front elevational view of FIG. 2;

FIG. 4 is a rear elevational view of FIG. 2;

FIG. 5 is a left side elevational view of FIG. 2;

FIG. 6 is a right side elevational view of FIG. 2;

FIG. 7 is a top view of FIG. 2; and,

FIG. 8 is a bottom view of FIG. 2.

Any elements shown in dash-dot broken lines form no part of the claimed invention in this Application, and are instead included to show environmental aspects of the claimed invention.
